US0D1006100S

(12) **United States Design Patent** (10) **Patent No.:** **US D1,006,100 S**
(45) **Date of Patent:** **** Nov. 28, 2023**

(54) **SMART GLASSES**

(71) Applicant: **Falcon Innovations Technology (Shenzhen) Co., Ltd**, Shenzhen (CN)

(72) Inventors: **Bin Zheng**, Shenzhen (CN); **Gang Xu**, Shenzhen (CN); **Mingjie Wang**, Shenzhen (CN)

(73) Assignee: **Falcon Innovations Technology (Shenzhen) Co., Ltd**, Shenzhen (CN)

(**) Term: **15 Years**

(21) Appl. No.: **35/515,289**

(22) Filed: **Sep. 19, 2022**

(80) **Hague Agreement Data**

Int. Filing Date: **Sep. 19, 2022**

Int. Reg. No.: **DM/223684**

Int. Reg. Date: **Sep. 19, 2022**

Int. Reg. Pub. Date: **Oct. 7, 2022**

(30) **Foreign Application Priority Data**

Aug. 8, 2022 (CN) 202230513207.4

(51) **LOC (14) Cl.** **16-06**

(52) **U.S. Cl.**

USPC **D16/309; D14/372**

(58) **Field of Classification Search**

USPC D16/100, 101, 300-342; D21/659, 660, D21/804, 807; D29/103-110

(57) **CLAIM**

The ornamental design for smart glasses, as shown and described.

DESCRIPTION

1. Smart glasses
2. Smart glasses
3. Smart glasses
4. Smart glasses
5. Smart glasses
- 1.1 : Front
- 1.2 : Back
- 1.3 : Left
- 1.4 : Right
- 1.5 : Top
- 1.6 : Bottom
- 1.7 : Perspective
- 1.8 : Perspective
- 1.9 : Perspective
- 2.1 : Front
- 2.2 : Back
- 2.3 : Left
- 2.4 : Right

(Continued)

2.5 : Top
2.6 : Bottom
2.7 : Perspective
2.8 : Perspective
2.9 : Perspective
2.10 : Perspective
3.1 : Front
3.2 : Back
3.3 : Left
3.4 : Right
3.5 : Top
3.6 : Bottom
3.7 : Perspective
3.8 : Perspective
3.9 : Perspective
3.10 : Perspective
4.1 : Front
4.2 : Back
4.3 : Left
4.4 : Right
4.5 : Top
4.6 : Bottom
4.7 : Perspective
4.8 : Perspective
4.9 : Perspective
4.10 : Perspective
5.1 : Front
5.2 : Back
5.3 : Left
5.4 : Right
5.5 : Top
5.6 : Bottom
5.7 : Perspective
5.8 : Perspective
5.9 : Perspective
5.10 : Perspective

The design is of a smart glasses used for augmented reality technology. **1.1-1.9** are drawings showing our smart glasses.

1 Claim, 49 Drawing Sheets
